[57] CLAIM

The ornamental design for element for flexible toy track, substantially as shown.

DESCRIPTION

FIG. 1 is a perspective view of an element of a flexible toy track showing my new design;
FIG. 2 is a perspective view of the rear side thereof;
FIG. 3 is a top plan view thereof;
FIG. 4 is a bottom plan view thereof;
FIG. 5 is a front elevational view thereof; and
FIG. 6 is an end elevational view thereof.
